Primary Examiner — Karen E Kearney*Assistant Examiner* — Alyse Joseph(74) *Attorney, Agent, or Firm* — Raj Abhyanker, P.C.(57) **CLAIM**

The ornamental design for a display screen with graphical user interface, as shown and described.

DESCRIPTION

FIGURE is a front view of a display screen with graphical user interface showing my new design.

The outermost broken line rectangle showing of a display screen and the other broken lines showing of portions of the graphical user interface form no part of the claimed design.

1 Claim, 1 Drawing Sheet
